EDGE-ACTIVE BELT

Paul B. Reeves, Columbus, Ind., assignor to
 Reeves Pulley Company, Columbus, Ind., a corporation of Indiana

Application May 3, 1951, Serial No. 224,305

6 Claims. (Cl. 74—236)

1

The present invention relates to power transmission belts and particularly to the type of belts intended to cooperate with coned sheaves. One type of such belt comprises a strand or web of material of high tensile strength, but being readily flexible both longitudinally and transversely, carrying a longitudinally spaced series of transversely extending block units. These units perform a dual purpose—they provide oppositely-facing surfaces outboard from the lateral edges of the belt strand for active engagement with the coned sheaves and act, at the same time, as transverse stiffener members for the belt strand to absorb the compressive stress which would otherwise be placed directly on the strand by the coned sheaves.

Belt units of the character here under consideration are usually formed of a relatively flat strand or web, the block units being either frictionally clamped to such strand or rigidly held thereto by means of screws passed through the strand body and engaged in the block units. Such means of securing the blocks to the strand give rise to obvious difficulties both in the manufacture and in the use of such belts. This invention is, therefore, directed primarily to an improved belt construction and particularly to an improved means for securing the block units to the belt strand.

Ancillary objects of the invention will appear as the description proceeds.

To the accomplishment of the above and related objects, my invention may be embodied in the form illustrated in the accompanying drawings, attention being called to the fact, however, that the drawings are illustrative only; and that change may be made in the specific construction illustrated and described, so long as the scope of the appended claims is not violated.

Fig. 1 is a central transverse section through a belt block constructed in accordance with the present invention;

Fig. 2 is a fragmental section taken substantially on the line 2—2 of Fig. 1 and looking in the direction of the arrows; and

Fig. 3 is a fragmental bottom perspective view of a section of belt strand used with this invention.

Referring more particularly to the drawings, I have illustrated, in Fig. 3, a portion of a belt strand 10 of the type used in my present invention. Such strand comprises a number of runs 28 of cord, wire or similarly strong tensile material, which runs may be independent of each other, and will preferably be separate turns or

2

stretches of a continuous element. Such runs, lying in a common plane, are integrally encased in a molded body of rubber or rubberoid material, which body is formed, on its under or inner surface, with uniformly-longitudinally-spaced, transversely extending cleats 11 of the body material. These cleats lend some transverse stiffness or rigidity to the belt strand; but more importantly, they will sustain substantial stresses, in the direction of strand length, without separation from the strand and without substantial distortion.

According to my invention, I associate with each cleat 11 a block unit 12 comprising a beam 13 having formed integrally at its opposite ends a pair of wing members 14 and 15. Said wing members present oppositely-facing surfaces 16 and 17, allochirally angularly related to a plane perpendicular to beam 13. Preferably, these members extend above and below the beam 13 and are wedge-shaped in side elevation as clearly shown in Fig. 2.

Beam 13 presents an upwardly facing surface 18, preferably part-cylindrical in cross-section as shown in Fig. 2, and extending continuously between the wing members 14 and 15 in the direction of the axis of cylindrical surface 18. A groove 19 is formed in surface 18 along the median line thereof and extends from one to the other of members 14 and 15 opening upwardly from surface 18.

Each block 12 is placed on belt strand 10 with beam surface 18 juxtaposed to the cleat-bearing side of strand 10 and with groove 19 snugly receiving one of the cleats 11. To retain cleat 11 in groove 19, I provide a clamp plate 20 adapted to register with beam 13 and engaging the outer surface of belt 10.

Plate 20 could be secured to beam 13 by means of screws passing therethrough and thence through holes formed in the belt strand 10 and engaged in threaded sockets in beam 13. This, however, would entail an added expense in manufacture in perforating the belt strand to accommodate passage of such screws, and would, at least to some extent, weaken the belt body. Therefore, I prefer to form plate 20 with a length substantially greater than the transverse dimension of strand 10, so that the ends 21 and 22 of said plate overhang the lateral edges of strand 10. A pair of screws 23 and 24 are passed through perforations in said ends and engage in threaded sockets 25 and 26 in beam 13, clearing the lateral edges of the belt strand, as shown. Thus, I eliminate the need for perforating the belt strand 10.

reducing the cost of manufacture, and maintaining maximum belt strength and life.

As in conventional practice, I provide friction pads 27 and 28 on the surfaces 16 and 17 for active engagement with the coned surfaces of the sheaves over which such a belt is intended to be run.

I claim as my invention:

1. A belt comprising a body strand of material of high tensile strength, but readily flexible both longitudinally and transversely, having a series of longitudinally-spaced, transversely-extending cleats on the inner surface thereof, and a plurality of longitudinally-spaced, transversely-rigid stiffener blocks each secured to said strand in registry with one of said cleats and each comprising a transverse beam integrally carrying members at its opposite ends formed to present oppositely-facing surfaces allochirally angularly related to a plane perpendicular to said beam, said beam being formed with an upwardly presented surface extending continuously between said members engaging the cleat bearing surface of said strand and having a central groove therein extending from one to the other of said members receiving therein one of said cleats, and means cooperating with said strand to secure said strand to said beam.

2. The belt of claim 1 in which said means comprises a clamping plate engaging the outer surface of said strand, in registry with said beam, having a length substantially greater than the transverse dimension of said strand, the ends thereof overhanging the lateral edges of said strand, and a pair of screws each penetrating one of said plate ends and engaging in a threaded socket formed in said beam for clamping said strand between said plate and said beam.

3. A belt comprising a body strand of material of high tensile strength, but readily flexible both longitudinally and transversely, having a series of longitudinally-spaced, transverse cleats extending continuously between the lateral edges of said body on the inner surface thereof, and a plurality of longitudinally-spaced, transversely-rigid stiffener blocks each secured to said strand in registry with one of said cleats and each comprising a transverse beam integrally carrying members at its opposite ends formed to present oppositely-facing surfaces allochirally angularly related to a plane perpendicular to said beam, said beam being formed with an upwardly presented, part-cylindrical, surface extending axially, continuously between said members engaging the cleat bearing surface of said strand and having a median groove therein extending from one to the other of said members and opening up-

wardly through said beam surface receiving therein one of said cleats, a clamping plate engaging the outer surface of said strand in registry with said beam, and means penetrating said plate and engaging said beam clamping said strand between said plate and said beam.

4. The belt of claim 3 in which said plate is of a length substantially greater than the transverse dimension of said strand, the ends thereof overhanging the lateral edges of said strand, and said means comprises a pair of screws each penetrating one of said plate ends and engaging in a threaded socket formed in said beam.

5. As an article of manufacture, a transverse stiffener block for belts comprising a rigid beam integrally carrying pressure-sustaining members at its opposite ends formed to present oppositely-facing surfaces allochirally angularly related to a plane perpendicular to said beam, said beam being formed with an upwardly presented, part-cylindrical surface extending axially, continuously between said members and having a median groove therein extending from one to the other of said members and opening upwardly through said beam surface.

6. An edge-active belt comprising a body strand of material of high tensile strength, but readily flexible both longitudinally and transversely, said strand being integrally provided with a series of longitudinally-spaced, transversely-extending cleats on one surface thereof, and a series of stiffener units each comprising a pair of cooperating elements, one of said elements of each pair registering with a cleat and having a groove receiving such cleat, one of said elements of each pair carrying, at its opposite ends and beyond the lateral edges of said strand, wing members presenting oppositely facing surfaces allochirally angularly related to a plane perpendicular to said element, the other element of each pair engaging the opposite surface of said strand and projecting laterally beyond the edges thereof, and screw means penetrating one of said elements, passing the lateral edges of said strand and threadedly engaging the other of said elements to clamp said strand between said elements.
